US0D1072677S

(12) **United States Design Patent** (10) Patent No.: **US D1,072,677 S**
(45) Date of Patent: ** Apr. 29, 2025

(54) **BICYCLE**

(71) Applicant: **Vassla AB**, Stockholm (SE)

(72) Inventor: **Christian Zanzotti**, Munich (DE)

(73) Assignee: **VASSLA AB (SE)**

(**) Term: **15 Years**

(21) Appl. No.: **29/856,523**

(22) Filed: **Oct. 14, 2022**

(30) **Foreign Application Priority Data**

May 11, 2022 (CN) 202230274993.7

(51) **LOC (15) Cl.** **12-11**

(52) **U.S. Cl.**

USPC **D12/111**

(58) **Field of Classification Search**

USPC D12/111, 117; D21/412, 414, 419,
